(57) **CLAIM**

The ornamental design for a paper input tray, as shown and described.

DESCRIPTION

FIG. 1 is a left-front perspective view of a paper input tray showing the new design;

FIG. 2 is a front view thereof;

FIG. 3 is a left side view thereof;

FIG. 4 is a right side view thereof; and,

FIG. 5 is a top view thereof.

The broken lines showing in FIGS. 1-5 are for illustrative purposes only and form no part of the claimed design.
